UNITED STATES PATENT OFFICE.

ERMY R. SMITH, OF MAPLEWOOD, NEW JERSEY, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

Application filed April 9, 1925. Serial No. 21,782.

This invention relates to telephone systems and more particularly to improvements in trunk circuits therefor used in the establishment of connections between manual exchanges.

The invention is adapted for use in systems in which calls received at one exchange by a so-called "A" operator are extended by means of a trunk circuit to an operator of a distant exchange commonly called a "B" operator who thereupon completes the call to the desired subscriber. In such systems, it is now usual for the "A" operator upon receiving a call from a calling subscriber and ascertaining the number desired, to employ a call wire leading to the desired exchange to communicate with the "B" operator. The "B" operator in responding, and after ascertaining the number desired and the exchange at which the "A" operator is located, will assign a trunk to the "A" operator. The "A" operator then connects the calling subscriber to said trunk, and the "B" operator extends the trunk to the called subscriber. This is known as the "call-wire" system.

The present invention is designed to provide a means for connecting switching trunks to an operator's telephone set, such as that of a "B" operator, so that traffic can be handled by the so-called "straight-forward" method of operation, wherein no "call-wire" is employed and the circuit from calling subscriber to called subscriber is progressively established without the necessity of one operator asking another which trunk she shall use. According to the present invention, the originating operator goes straight forward and chooses a trunk herself so that when the call is placed in the hands of the terminating or "B" operator the connection has already been established that far.

It is an object of the invention to provide a means whereby upon the selection of an idle trunk leading to a distant exchange by an "A" operator, the "B" operator may manually connect such trunk to her set and at the same time automatically notify the "A" operator that she, the "B" operator, is ready to receive the designation of the

called line. After receiving the number of the desired subscriber from the "A" operator, the "B" operator will thereupon complete the call in the usual manner.

55

A feature of the invention comprises a means whereby a momentary tone is transmitted over the switching trunk to the "A" operator when the "B" operator connects such trunk to her set.

60

Another feature of the circuit arrangement is the provision of means to enable the "B" operator to complete a connection to the subscriber's line by removing a plug from a first jack to which a call had been extended and inserting it into a second jack.

65

A further feature resides in an arrangement for employing this invention in systems using the call circular method of operation so that a position using this "straight-forward" method of trunking can also handle traffic of adjacent positions arranged for call circuit operation. When the operator's set of a position employing the present invention is arranged for connection to a call circuit position, provision is made for transmitting a signal to an operator at the outward end of the call circuit in case the straight-forward position is busy answering a call. This tone notifies the "A" operator at the outward end of the call circuit that the inward operator is not yet free to answer. After the inward operator completes the call, the tone will cease and the call circuit operator will then be connected to the "B" operator at the straight-forward position. It may be seen, therefore, that the system is adaptable for use with the present method of call circuit operation and its flexibility enables its use without modifying existing systems.

90

Another feature of the present invention is the provision of a plurality of jacks leading to the operator's headset and the provision of means associated therewith to render effective one of said jacks at a time. By means of this feature the operator may insert a second incoming trunk into one of these jacks while she is still communicating with an operator over a first trunk so that when she removes the plug of the first to complete a connection to a called line the

100

second will immediately become effective. By the provision of this means the service may be quickened and delays due to the mechanical handling of the apparatus reduced to a minimum.

One embodiment of the invention is illustrated in the accompanying drawing which illustrates one form of the invention. In Fig. 1, A shows a trunk leading from an outgoing exchange which desires a connection with an operator at the local exchange. Only the portion of the trunk terminating at the local exchange is shown. B illustrates a listening circuit to which the trunk circuit may be connected. Fig. 2 represents a subscriber's line jack. Only those portions of the circuit arrangement necessary to a proper understanding of the invention are shown.

A detailed description of the invention will now be given. Assuming that an "A" operator at an outgoing exchange desires to be connected to a subscriber at the exchange wherein circuit B is located; she will therefore connect to the calling subscriber in the usual manner and extend the connection by seizing a trunk leading to the desired exchange, in this instance, the exchange at which circuit B is situated. Assuming that the jack into which the "A" operator plugs is that associated with trunk A, a signal will be forwarded at the incoming exchange to light lamp 1. The operation of lamp 1 is effected as follows: grounded battery of relay 2, left-hand winding of relay 2, normal make-before-break contact of relay 3, lower right-hand winding of repeating coil 4, through the loop at the calling, "A" operator's end, back through the upper right-hand winding of repeating coil 4 and the outer normal contacts of relay 3 to ground through the right-hand winding of relay 2. Relay 2 will thereupon pull up its armature and cause the actuation of lamp 1 in a circuit from grounded battery, filament of lamp 1, normal right-hand contacts of relay 5, left-hand winding of relay 3 to ground through the armature and alternate contacts of relay 2. The operator at this exchange will thus be apprised that there is a call over trunk A associated with lamp 1 that awaits connection to a subscriber at this exchange.

Relay 3 due to the energization of its left-hand winding, will attract its armature to break the normally closed contacts thereat and supply a ground for relay 2. The left-hand winding of relay 2 will now be maintained energized by this ground. It is seen therefore that the actuation of relay 3 causes the circuit leading to the "A" operator to be broken.

The operator at this end will immediately take plug 6 of trunk A associated with lamp 1 and insert it into a listening jack such as

7 or 8. Assuming that she plugs into jack 8, a circuit will be closed from grounded battery through supervisory relay 9 of the trunk, lower left-hand winding of repeating coil 4 through the ring of the plug and jack, inner left-hand normal contacts of relay 10 in the listening circuit, lower left-hand winding of repeating coil 11, through the winding of relay 12 to ground. Supervisory relay 9 operates in this circuit and closes a circuit for the operation of relay 3 as follows: Grounded battery, right-hand winding of relay 3 operated contacts and armature of relay 9, left-hand winding of relay 3 to ground through the operated contacts and armature of relay 2. Relay 3 therefore is controlled to maintain its armatures in a position that keeps open the circuit leading to the "A" operator. The reasons therefor will be hereinafter set forth. Relay 12 operates and provides a ground for sleeve relay 5 in the trunk, which operates and causes the extinguishment of lamp 1. The circuit therefore extends from grounded battery, winding of relay 5, sleeve of the plug and jack respectively, winding of relay 13, normally closed armature and contacts of relay 10 to ground through the right-hand armature and contacts of relay 12 to ground. Relay 12, by pulling up its left-hand armature will also close a circuit for relay 14, through the normal make-before-break contacts of relay 15.

It is of note therefore that sleeve relay 5 in the trunk circuit does not operate until after supervisory relay 9 has operated. This is for the purpose of keeping relay 3 energized and preventing the switching trunk from functioning to transmit a false signal to the "A" operator, upon the insertion of plug 6 into jack 8. If this feature were not provided, and the signaling circuit to the "A" operator not broken, the lamp 35 or other means, at the "A" operator's position would be caused to operate upon the insertion of plug 6 into jack 8. This false signal would erroneously be construed by the "A" operator to indicate that the "B" operator had connected to the called subscriber; and hence the "A" operator would ring over the line. However, with this means, as above outlined, no such false signal is flashed and hence the "A" operator will not ring. This prevents a so-called false plugged-up signal to the "A" operator. Of course, after the "B" operator removes the trunk plug from jack 8, and inserts it into the called subscriber's jack 18, as will hereinafter be disclosed, the "A" operator will then be signaled in the usual manner and will apply ringing current to the line.

It has been seen that relay 13 operated in the circuit for relay 5. This is for the purpose of disconnecting the tip, ring and sleeve conductors from jack 7 in order to prevent

false operation in case the operator plugs another switching trunk into this jack before plug 6 is withdrawn from jack 8.

Relay 14 operated after the operation of relay 12 and by pulling up its inner left-hand armature connects a tone to the line from source 16. Also it supplies ground for the operation of relay 15 through its right-hand armature. Relay 15 in operating will lock up to ground through the left-hand armature and contacts of relay 12 and will remain operated under the control of said relay 12. Relay 15 in locking to this relay will obviously cause a deenergization of relay 14. By making relay 14 slow to release and relay 15 slow to operate the duration of the tone transmitted back to the "A" operator may be accurately timed.

Upon the release of relay 14, relay 17 will operate in a circuit as follows: Grounded battery, winding of relay 17, outer restored left-hand contacts of relay 14, armature and right-hand contacts of relay 15 to ground. Relay 14 in releasing will cut off the tone from the line and relay 17 which operates immediately thereafter will through the outer armatures thereof now connect the operator's telephone set to the line. The operator will therefore be in direct communication with the "A" operator at the forwarding exchange and will be ready to receive the designation of the called subscriber without any oral request on her part. Upon receiving the number of the called subscriber, the "B" operator will remove plug 6 from jack 8 and insert plug 6 into the called subscriber's jack 18 to complete the connection. Upon the withdrawal of plug 6 from jack 8, the supervisory relay will lose its holding ground and release. Supervisory relay 9 will also release. This will cause relay 3 to release and obviously close the circuit for the operation of the signal 35 at the "A" operator's position. As the plug 6 is inserted into jack 18 a circuit including sleeve relay 5 and cut-off relay 19 is closed and both these relays operate. As the loop of the called subscriber's line is open at this time, the relay 9 does not operate and hence lamp 1 remains dark and relay 3 does not operate as before. The "A" operator will then know that the trunk is "plugged-up" to the called subscriber and will thereupon ring over the line.

Relay 14 is purposely made slow in releasing and relay 15 is made slow in operating, in order that the release of these relays will make the circuit function to transmit the momentary tone, described, over the switching trunk to the "A" operator. This tone indicates to the "A" operator that the switching trunk operator is being connected to the trunk and ready to receive the call. As has been seen, after she receives details of the call, she withdraws plug 6 from the jack, releasing

all the relays in the switching trunk; makes the usual busy test and completes the call.

When the called subscriber answers, supervisory relay 9 operates, whereupon relay 3 becomes operated. This operation cuts off 70 battery and ground from the distant A operator and causes the extinguishment of lamp 35 as a signal that the subscriber has answered. Relay 3 also locks in relay 2 and hence the lamp 1 remains dark until the called subscriber hangs up. When this happens relay 9 returns to normal and releases relay 3, whereupon relay 2 is again connected to the distant A operator and lamp 35 is 80 lighted as a signal that the conversation has ended. The A operator then opens the loop at her end of the trunk and relay 2 releases, whereupon lamp 1 becomes lighted in a circuit including the back contact of relay 2 and the front contact of relay 5. This is 85 a signal to the B operator to remove plug 6 from jack 18.

This circuit is also arranged for connection to incoming call circuits, as indicated on the drawing, so that traffic of call circuit positions may be handled from a position arranged for straight-forward operation. Call circuits may be arranged in the usual manner to be connected through any usual means, such as a grouping key. As illustrated in the drawing, the leads of the call circuits shown are normally connected to an operator's telephone set, through the contacts of relay 17. It is evident therefore that if the operator is busy answering a call with the listening jack circuit, relay 17 will be operated and the operator's set disconnected from the call circuit leads. Instead, the call circuit will be connected to tone 16. This tone notifies the operator at the outward end of the called circuit that the inward operator is not yet free to answer the call. Obviously, after relay 17 restores, the call circuit leads will again be connected to the operator's set and disconnected from the tone. The call circuit operator will then pass the call in the usual manner. It is evident that any number of call circuits and any number of listening jack circuits may be multiplied together, but for purposes of this invention, only one set of call circuit leads and two listening jacks are shown.

If jack 7 were used instead of jack 8, in the operation set forth, relay 10 would function in a similar manner as does relay 13 and in place thereof. Thus, if jack 7 were seized and a second switching trunk associated therewith, before a first trunk in jack 8 was removed, relay 13 would prevent the connection of the tip, ring, and sleeve conductors to jack 7, and hence assure the seizure of the listening circuit by only one trunk at a time. Upon the removal of the first trunk from jack 8, the second trunk, in jack 7, would, as has been described, be connected to the listen-

ing circuit, and relay 10 operate to prevent false operation upon the possible seizure of the other jack, and so on.

It should further be noted that relays 10 and 13 are slow to release, so that if there is a plug in both jacks 7 and 8 and the one in jack 8 is effective, relay 13 will be operated and when the plug in jack 8 is removed, relay 13 being slow to release its armatures 10 will give relay 12 time to become deenergized. Thereupon relay 15 will return to normal, so that upon the complete release of relay 13 and the subsequent energization of relay 12, the tone current from source 16 will 15 be momentarily applied to the trunk now connected through jack 7.

It is seen, therefore, that only one of the jacks is effective at a time, even though a second jack is seized while a first is still busy. 20 The operator may, as a result, handle the apparatus to its full capacity, by answering and completing calls practically contemporaneously due to a plurality of jacks being available to her, without fear of causing 25 fused or false operation.

What is claimed is:

1. In a telephone system, a trunk circuit, an independent circuit having listening means associated therewith and adapted to 30 be connected to said trunk, a source of tone current, and means responsive to the connection of said trunk circuit to said independent circuit to automatically and sequentially connect said source of tone current to 35 said trunk, to disconnect said source of tone current from said trunk and to connect said listening apparatus to said trunk.

2. In a telephone system, a first trunk of a certain character, a second trunk of 40 a different character, an operator's headset normally connected to said first trunk, means for connecting said headset to said second trunk, a source of tone current, and means for connecting said source of tone current 45 to said first trunk upon the disconnection therefrom of said headset and the connection of said headset to the other trunk.

3. In a telephone system, a trunk of a certain character, an operator's telephone set 50 normally connected to said trunk, trunks of other character, means for connecting said headset to said other trunks, a source of tone current, and means for connecting said source of tone current to said trunk of a 55 certain character, upon the disconnection of said telephone set therefrom.

4. In a telephone system, a plurality of trunk circuits, an independent circuit having listening means associated therewith and 60 adapted to be connected to any of said trunks, means for associating more than one of said trunks with said independent circuit at one time, means for rendering effective only one such connection at a time, 65 means for automatically rendering effective

another such connection upon the breaking of a previously effective connection, a source of tone current, and means responsive to the effective connection of one of said trunk circuits with said independent circuit for automatically and sequentially connecting said source of tone current to said trunk, disconnecting said source of tone current from said trunk and connecting said listening apparatus to said trunk. 70 75

5. In a telephone system, a plurality of trunk circuits terminating in plugs, a plurality of jacks, a telephone headset associated with said jacks, means for successively associating said trunks with said 80 jacks, means responsive thereto for successively associating said telephone set to said trunks, said set being automatically connected to only one of said trunks at one time in the order of their connection to said jacks, 85 a source of tone current, and means responsive to said second mentioned means for momentarily connecting said source of tone current to said trunks.

6. In a telephone system, a call wire circuit, a trunk circuit, an independent circuit having listening apparatus associated therewith, means operative responsive to the interconnection of said trunk circuit with said independent circuit to connect the listening 90 apparatus thereto, a source of tone current, and means responsive to said interconnection for connecting said source of tone current to the said call wire circuit. 95

7. In a telephone system, a first trunk, a second trunk, an independent circuit adapted to be connected to said trunks and having listening apparatus associated therewith, a characteristic signaling means, means responsive to the connection of said circuit 100 with one of said trunks to momentarily associate said signaling means therewith, means operative responsive thereto for connecting said listening apparatus to said trunk and transferring the connection of 105 said signaling means to the other of said trunks. 110

8. In a telephone system, a plurality of telephone exchanges, an exchange X, trunk lines of a certain character leading from some of said telephone exchanges to exchanges X, trunk lines of a different character leading from other of said exchanges to exchange X, listening apparatus at said exchange X, said listening apparatus being 115 normally connected to trunks of a certain character and means responsive to the connection of said telephone equipment to trunks of another character for disconnecting said listening apparatus from the trunks 120 normally connected thereto. 125

9. In a telephone system, a trunk terminating in a plug, listening apparatus associated with a jack, a subscriber's line terminating in another jack, a signal, means re- 130

sponsive to the connection of said trunk with the first of said jacks for connecting said listening apparatus to said trunk and maintaining said signal in a certain condition, and 5 means responsive to the connection of said trunk with the other of said jacks for changing the condition of said signal.

10. In a telephone system, a trunk line terminating in a plug, listening apparatus associated with a jack, a subscriber's line terminating in another jack, a signal, means responsive to the connection of said trunk with the first of said jacks for connecting said listening apparatus to said trunk, and means 15 responsive to the connection of said trunk with the other of said jacks for disconnecting said listening apparatus from said trunk and for actuating said signal.

11. In a telephone system, a trunk circuit terminating in a plug, a relay in said trunk circuit for controlling a signal therein, another circuit terminating in a jack, a master relay in said other circuit, a subscriber's line terminating in a jack, a means responsive to 25 the connection of said trunk with said other circuit, under the control of said master relay, for operating said relay in the trunk circuit and maintaining the signal therein in a desired condition, and means responsive to 30 the disconnection of said trunk from said other circuit and its connection to said subscriber's line for causing the restoration of said relays and a change in the condition of said signal.

35 12. In a telephone trunking system, a trunk terminating in a plug, telephone listening apparatus associated with an independent circuit terminating in a jack, a mas-

ter relay in said independent circuit, a second relay under the control of said master 40 relay and a third relay, means operative responsive to the interconnection of said trunk and independent circuit for causing said master relay to operate and effect the actuation of said second relay, means responsive 45 to the actuation of said second relay to cause the operation of said third relay and the release of said second relay, a fourth relay, and means under the control of said second and third relays for causing a momentary tone to 50 be connected to said trunk and for causing the immediate connection of said listening apparatus to the interconnected circuits under control of said fourth relay, said tone being disconnected from the trunk upon the 55 connection of the listening apparatus thereto.

13. In a telephone system, a plurality of trunk circuits terminating in plugs, an independent circuit having a plurality of jacks associated therewith, listening apparatus associated with said independent circuit, means responsive to the interconnection of a plurality of trunks with said circuit by the respective connection of the plugs thereof with said jacks for connecting said listening apparatus with one of said trunks, and for connecting said listening apparatus to a second of said trunks upon the removal of the plug of the first trunk from a jack of said circuit, a source of tone current, and means responsive to said first mentioned means for momentarily connecting said source of tone current to said trunks.

In witness whereof, I hereunto subscribe my name this 8 day of April A. D., 1925.

ERMY R. SMITH.
